W. F. CREMEAN.
HOPPER DOOR LOCKING DEVICE.
FILED JAN. 12, 1922.

2 SHEETS-SHEET 2

UNITED STATES PATENT OFFICE.

WILLIAM F. CREMEAN, OF TOLEDO, OHIO.

HOPPER-DOOR-LOCKING DEVICE.

Application filed January 12, 1922. Serial No. 523,687.

To all whom it may concern:

Be it known that I, WILLIAM F. CREMEAN, a citizen of the United States of America, residing at Toledo, in the county of Lucas 5 and State of Ohio, have invented certain new and useful Improvements in Hopper-Door-Locking Devices, of which the following is a specification.

My invention relates to new and useful 10 improvements in hopper door locking devices and has for an object to provide locking means that will first support the doors in a temporary nearly closed position and from which position the doors may then be pried 15 or forced to their closed position, at which point they may be easily locked.

Still another object of the invention is to provide a locking device for hopper car doors where two doors are positioned with 20 their inner free ends adjacent when closed, and to provide a locking device wherein each of the doors carries a member that will be used as a fulcrum point for a bar or lever so that when the doors are in a temporary sup- 25 ported position the fulcrum point on one door will be used so that the other door may be lifted to its closed position, after which the closed door provides the fulcrum point so that the remaining open door may be 30 pried or forced shut.

Still another object of the present invention is to provide a locking device for hopper doors where the inner free ends of the doors are adjacent, and across each of the doors is 35 preferably positioned an angle iron which extends outwardly beyond the sides of the door, while the ends of the angle irons are provided with small holes or openings there- 40 in. To be located above the outstanding ends of each of the angle irons are positioned 45 hooks which are adapted to engage the free ends of the angle irons and support the doors first in a partly closed position after which a bar will be thrust through the openings mentioned in the ends of the angle irons so 50 that first one door by an upward movement of the rod will be closed, after which a downward movement of the bar, while still in the same holes, will close the other door.

Still other objects of the invention are to 55 provide locking means so that it is relatively easy to operate the doors to a closed position, after which time the pivotal dogs will be forced downwardly to hold the supporting members of the locking means in a locked

position, thereby preventing any accidental opening of the doors.

Still other objects of the invention are to provide locking means that are relatively cheap to manufacture, quickly and readily 60 applied to the hopper doors, compact in nature and relatively light in weight.

With these and other objects in view, the invention consists in certain new and novel 65 constructions and combination of parts as will be hereinafter more fully described and pointed out in the claims.

Referring now to the drawings showing a preferred embodiment of the invention,

Fig. 1 is a diagrammatic view of a hop- 70 per car showing my improved locking mechanism as applied to the hopper doors.

Fig. 2 is a view in side elevation showing a fragmentary portion of a side of a car and the locking devices supporting the doors of 75 the hopper in their closed and locked position.

Fig. 3 is a similar view but showing one of the doors in a temporary supported position, the other door being in its closed and locked 80 position, and

Fig. 4 is a fragmentary detailed section taken on line 4-4 of Fig. 3.

In the several views, I have only illus- 85 trated the locking devices as applied to the hoppers, on one side of the car, but it is to be understood that the arrangement on the other side of the hoppers and doors is identi- 90 cal, so that an illustration and description of the locking device as applied to one side of the doors and hopper equally well applies to the other side.

Referring now more specifically to the drawings, and the invention illustrated, there is shown diagrammatically a standard 95 type of hopper car 1, a portion of a side sill 2, a fragmentary top of the hopper side 3, and a plate 4 which is bolted at its top to the side sill 2, which forms the major outer side of the hopper. Supporting straps 5 are 100 angularly disposed with regard to the side sill 2, which may be riveted at their upper ends as at 6 through the plate 4 and the side sill 2, and which are also bolted as at 7 to the plate 4, and the sides 3, and may be riveted or bolted to the sloping bottom walls 8 of the hopper chute and are designed to extend completely under the hopper and be similarly secured on the other side of the 105 car and hopper.

Preferably hinged to these bottom sloping walls 8 of the hopper and to the supporting straps 5, are the two doors 9 and 10, which, as will be noticed, have their inner free edges 5 adjacent, when in their closed position.

The doors may be reinforced by forming the hinges 11 with long legs which may extend nearly to the free edges of the door, and which may be secured to the doors by the 10 bolts 12.

Near the outer or free edges of the doors are the angle irons 13 and 14, each of which extend completely across its door and out beyond its free edges or sides to thereby 15 provide ledges or brackets that are to be engaged by pivotal hooks, shortly to be described.

These angle irons are each bolted or riveted to the under side of the doors, the bolts 20 passing through the legs of the hinges and each is disposed in the opposite direction, or in other words with the upper legs each extending towards the hinged connection of its door. In the vertical legs of these angle 25 irons and in the portion which extends beyond the free sides of the doors are the openings 15 and 16, which form fulcrum points as will shortly be described.

Referring now to the supporting members, there are shown as securely riveted to the plate 4 the housings 17 and 18 in which are pivotally mounted respectively the two 30 hooks 19 and 20, while within the housings and to the rear of each hook are pivotally 35 mounted the dogs 21 and 22 which are provided respectively with the lugs 23 and 24 which form striking surfaces so that the dogs may be swung rearwardly when desired.

40 Along the lower edge of the plate 4 is shown the reinforcing member 25 to strengthen this plate at this point and to prevent the locking devices from being torn from the plate 4.

45 It will be noticed that the housings 17 and 18 are oppositely positioned so that the hooks contained therein will also be oppositely positioned and it will also be seen that the hooks are provided with auxiliary ledges 50 26 and 27 respectively as well as the main supporting ledges 28 and 29 respectively, so that the door 9 may first be supported through the upper leg of the angle 13 on the ledge 26 of the hook 17, while the door 55 10 will be supported on the ledge 27 of the hook 20 by the upper leg of the angle 14.

60 It is well known to those skilled in the art that it is relatively an easy matter to swing the hopper doors to a partly closed position, but to entirely close the doors, relatively great force is necessary as the doors often become warped or distorted in service so that they have to be sprung or forced before they can be finally closed.

65 In the present embodiment, however, both

doors may be manually lifted upwardly until they are both supported on the temporary ledges 26 and 27 of the two hooks 19 and 20, after which a bar or rod 30 may be placed through the holes 15 and 16 formed 70 in the angles 13 and 14 and an upward pressure at the outer end of the bar 30 will raise the door 9 to its closed position after which the dog 21 may be revolved to assume the position shown in Fig. 3 which will tightly 75 hold this door in its final and locked position.

This closing movement is possible as the inner end of the bar 30 will be fulcrumed in the opening 16 of the angle 14 of the door 80 10, while to close the door 10 only necessitates a downward movement of the bar 30 at its outer end so that the angle 13 now acts as a fulcrum point and the inner end of the bar will force the door 10 upwardly 85 to its closed position, after which the hook 20 may be forced under the upper leg of the angle 14 so that the ledge 29 will engage the upper leg of the angle at which time the door will be supported in its closed position. 90 To lock the same, it will only be necessary to force the dog 22 against the rear edge of the hook, thereby making it impossible to have the hook become disengaged from the upper edge of the angle iron. 95

Although in Fig. 3 I have shown the bar first inserted through the angle on the left hand door, it will be understood that the bar may be inserted first from either side when the two doors are in their temporary 100 supported position, the angles on both of the doors acting as fulcrums for each other.

To open the doors, the dogs, of course, will be swung rearwardly and the hooks forced away from each other, which will 105 allow the doors to drop and if, for any reason, one of the doors should become jammed, of course, a bar may be used through the fulcrum points to pry it open.

It will be seen that the operation is extremely simple as a lifting movement on the bar will close one door where it may be quickly locked and a prying movement will close the other door without even the removal of the bar from the openings in 110 the two angle irons.

In most instances, as heretofore mentioned, a similar arrangement will be used on both sides of the car and hoppers so that the doors will be supported from their two 115 sides.

From the foregoing it will be seen that I have provided an extremely simple and efficient locking arrangement for hopper car doors wherein both doors may be temporarily supported in a partly closed position, from which position one may quickly be lifted into place, and the other pried into place by the use of a bar or rod inserted through the convenient fulcrum points 120 130

formed in the outer ends of the angles, which angles also provide brackets or ledges to be engaged by the supporting hooks.

Furthermore, I have provided a locking 5 arrangement that is extremely compact in nature, relatively cheap to manufacture, and light in weight in comparison with the many hopper door locking devices now in general use.

10 Many slight changes might be made without in any way departing from the spirit and scope of the invention.

Having thus described my invention, what I claim as new and desire to secure by Letters Patent is:

1. In a door device for railway cars, a plurality of doors hinged to the car body, means carried by the car body for supporting the doors in partially closed or fully closed positions, and means in said doors adapted to receive means operable upon one door for forcing another door from partially closed to fully closed position.

2. In a door device for railway cars, a plurality of doors hinged to the car body, means carried by the car body for supporting the doors in partially closed or fully closed positions, and means in said doors adapted to receive removable means extending from one door to another door for forcibly moving one of the doors from one of said positions to the other position.

3. In a door device for railway cars, a plurality of doors hinged to the car body, means carried by the car body for supporting the doors in partially closed or fully closed positions, and means in said doors adapted to receive means extending from one door to another door for forcibly moving either of the said two doors from one of the said positions to the other position.

4. In a door device for railway cars, a plurality of doors hinged to the car body, means carried by the car body for supporting the doors in partially closed or fully closed positions, and means in said doors adapted to receive means reacting upon one door for forcing the other door from one of said positions to the other position.

5. In a door device for railway cars, a plurality of doors hinged to the car body, means carried by the car body for supporting the doors in partially closed or fully closed positions, a fulcrum affixed to each of the doors, the same being adapted to receive a lever operable upon the fulcrum of one door for forcing another door from one of said positions to the other position.

6. In a door device for railway cars, a pair of doors hinged to the car body, means carried by the car body for supporting the doors in partially closed or fully closed positions, a pierced bracket affixed to each of the doors, the orifices thereof being substantially in alignment when the doors are

in either of the said positions, said orifices being adapted to accommodate a lever insertable through the said orifices and operable upon one of said brackets for forcing the opposite doors from one of said positions to the other position.

7. In a door device for railway cars, a pair of doors hinged to the car body, means carried by the car body for supporting the doors in partially closed or fully closed 70 positions, a fulcrum formed upon each of the doors, said fulcrums being formed and arranged in such manner as to accommodate a lever operable in one direction and upon the fulcrum on one of the doors for forcing 75 the opposite door from one of said positions to the other position, and being also operable in the opposite direction and upon the fulcrum on the other door for forcing 80 the first mentioned door from one of its 85 said positions to the other.

8. In a door device for railway cars, a pair of doors hinged to the car body, means carried by the car body for supporting the doors in partially closed or fully closed 90 positions, a fulcrum formed upon each of the doors, said fulcrums being formed and arranged in such manner as to accommodate a lever extending between the fulcrums of both doors, and operable thereupon in such 95 manner as to produce simultaneous reactions in opposite directions upon the two fulcrums.

9. In combination with a hopper car, a pair of hinged doors having their free ends 100 adjacent when in their closed position, an angle iron secured to the bottom of each door and extending beyond the free sides of the door, said angle irons oppositely disposed with respect to each other, a pair of hooks pivotally mounted on the side of the hopper and positioned above the outstanding ends of said angle irons, each of said hooks provided with an auxiliary and main supporting ledge, the doors adapted to be 105 supported first on the auxiliary ledges of said hooks through the medium of said angle irons, fulcrum points formed in the ends of said angle irons for the reception 110 of a bar so that an upward movement of the bar will raise one door so that its angle iron will be supported by the main supporting ledge of its hook, after which a downward movement of the lever will close the other of said doors so that its angle iron 115 will be engaged by the main supporting ledge of its hook and means for locking the hooks in engagement with said angle irons.

10. In combination with a hopper car, a 125 pair of hinged doors having their free ends adjacent when in their closed position, an angle iron secured to the bottom of each of said doors and extending beyond the sides 130 of the doors and oppositely faced with re-

lation to each other, the ends of the said angle irons being provided with small openings therein and substantially registering so that a bar may be passed through both 5 of said openings at one time, hooks pivotally mounted above said angle irons and also oppositely faced to engage the ends of said angle irons, main and auxiliary ledges formed on each of said hooks for first sup- 10 porting the doors in a temporary position, the said openings forming fulcrum points so that when a bar is passed within the said opening an upward movement of the bar

will force one door to a closed position, the angle iron of said door to be engaged by the main supporting ledge of said hook, after which a downward movement of the lever will close the opposite door so that its angle iron will be engaged by the main supporting ledge of its hook, and means for 20 locking both of the hooks in engagement with said angle irons.

In testimony whereof I affix my signature.

WILLIAM F. CREMEAN.
